New York, N. Y., a corporation of New York

Application December 9, 1944, Serial No. 567,509

2 Claims. (Cl. 18—16)

1

This invention relates to control apparatus and more particularly to automatic control apparatus for hydraulic presses.

It is an object of the present invention to provide a highly sensitive control apparatus for controlling the operation of a hydraulic press under the influence of parts discharged from the press.

In accordance with one embodiment of the invention, a hydraulic molding press is provided with a control circuit for automatically supplying fluid to actuate the press, which control circuit operates under the control of articles discharged from the press and includes a tiltable article-receiving tray or table positioned to receive an article discharged from the press and mounted on a pantograph type leverage mechanism adapted to be actuated by the weight of the article to carry the table to a position to be tilted on the next stroke of the press whereby very light articles may be effective to control the press circuit.

A complete understanding of the invention may be had by reference to the following detailed description when considered in conjunction with the accompanying drawings, wherein

Fig. 1 is a diagrammatic view, partly in cross section, of a molding press equipped with a control device made in accordance with the present invention;

Fig. 2 is a plan view showing the table or tray for receiving a molded article from the press and the supporting bracket for the table;

Fig. 3 is a fragmentary detail sectional view taken substantially along the line 3—3 of Fig. 2 in the direction of the arrows showing a detail of the support mechanism for the tiltable table;

Fig. 4 is a fragmentary detail view, partly in section, of another portion of the table supporting mechanism taken substantially along the line 4—4 of Fig. 2 in the direction of the arrows;

Fig. 5 is a fragmentary detail sectional view taken substantially along the line 5—5 of Fig. 2 showing a detail of a switching mechanism operable by the table; and

Figs. 6 and 7 are vertical sectional views taken substantially along the line 6—6 of Fig. 2 in the direction of the arrows and showing the table in its upper and lower positions, respectively.

Referring now to the drawings, wherein like reference characters designate the same parts throughout the several views, particular reference being first had to Fig. 1, it will be seen that applicant's apparatus is adapted for use with a molding press of the type comprised of suitable standards 11 joined by a cross head 12 and having a

2

resilient press bed 13 interposed between them. The press bed carries the usual die block 14 adapted to cooperate with a movable die member 15 mounted upon the lower end of a piston rod 16. The piston rod 16 is connected to a piston 17 adapted to be reciprocated in a cylinder 18 suitably mounted on the cross head 12. The cylinder 18 may have fluid under pressure fed to either its upper or lower end by an upper feed pipe 19 or a lower feed pipe 20, which are supplied with fluid under pressure through a four-way valve 21 having an inlet pipe 22 and an outlet pipe 23 connectable to either one of the upper or lower feed pipes. The valve 21 is of the solenoid actuated type having a control lever 24 suitably connected to a core member 25 associated with a pair of solenoid coils 26 and 27. The solenoid coils 26 and 27 are connected to a timing mechanism 28 of any suitable type adapted to supply current alternately to the two solenoid coils 25 and 26 to effect the automatic operation of the press.

The timer 28 operates under control of a momentary contact start switch 29 and a pair of contacts 30 and, upon closure of the switch 29, the timer will start to operate. The timer controls the supply current to the coil 27 for operating the valve 21 to feed fluid under pressure through the pipe 20 to the lower end of the cylinder 18 to raise the movable die member 15. When the press has been loaded with material to be pressed, the timer will cause the solenoid coil 26 to be energized, thereby to shift valve 21 and feed fluid to the upper end of the cylinder 18.

There may be connected to the timer, in any suitable manner, a feeding mechanism (not shown) for feeding moldable material through a nozzle 42 properly aligned with a die 43 in the die block 14 and after an article has been formed between the die 43 and a cooperating die 44 on the movable die member 15, air may be directed under pressure through a nozzle 41 to eject the part into a guide chute 40 suitably positioned at the back of the press. In addition to the mechanisms just described, means are provided for ejecting the part from the die 43 on the upstroke of the piston 17 and these means have been illustrated as a linkage 45, which will push a molded part out of the die 43 and into the path of the air from the nozzle 41. The linkage 45 carries a lever actuating collar 46 which, when the movable die member 15 approaches its lowermost position, will engage and actuate a lever 47 pivoted on the press standard 11. The lever 47 is provided with a slot 49 adapted to receive a pin

50 on a bell crank lever 51, which is suitably pivoted on the standard 11.

Mounted upon a downwardly projecting portion of the bed 13 is a U-shaped frame 52, which serves to support the chute 40 and in which a trap supporting frame, designated generally by the numeral 53, may be mounted. The trap supporting frame 53 comprises a pair of side plates 54 and 55 (Fig. 2), which are joined together adjacent their lower edges by a tubular brace 56 and are joined together adjacent their upper lefthand end (Figs. 6 and 7) by an angle member 57. The angle member 57 and tubular brace 56 may be suitably secured to the side plates 54 or 55 in any suitable manner, for example, by welding them together. Adjacent its lower end, the U-shaped frame 52 has a cross brace 58 extending between its sides, upon which the trap supporting frame 53 rests, notches 59 being formed in the side plates 54 and 55 to receive the cross brace 58 and nut and bolt assemblies 60 extending through the sides of the frames 52 and 53 serving to hold the trap supporting frame 53 on the U-shaped frame. In order to more rigidly support the trap supporting frame 53 on the frame 52, S-shaped clamps 95 are attached to the side plates 54 and 55 by means of nut and bolt assemblies 96.

The side plates 54 and 55 are bent adjacent their ends, as shown most clearly in Fig. 2, to receive a shaft 61 (Fig. 4) on which a tube 62 is rotatably mounted. Adjacent the lower ends of the outwardly bent portions of the side plates 54 and 55, as seen most clearly in Fig. 4, bearings 63 are attached to the side plates for receiving stud shafts 64. The stud shafts 64 cooperate with the tube 62 to support a pantograph structure comprising two upper levers 65 and two lower levers 66. The levers 66 are freely rotatable about the stud shafts 64, whereas the levers 65 are attached to the tube 62 in any suitable manner, whereby the tube 62 will rock about its shaft 61 when the levers 65 are moved. The rearwardly extending ends of the levers 65 extend through a weight 67, which is adjustably held on the ends of the levers by nuts 68 threaded onto the ends of the levers. The rearwardly extending ends of the levers 66 are likewise threaded and are adapted to receive two knurled weights 69 and 70, the position of which may be adjusted on the levers 66 to balance the levers, and also to counterbalance all except one part of several that may be processed simultaneously if the apparatus is set up to process a plurality of parts at one time.

At their right ends, as best shown in Figs. 2, 6 and 7, the levers 65 and 66 are linked together by vertically extending links 80 and the links 80 are joined together by a flanged cross brace 81 (see also Fig. 3). The upper ends of the links 80 have apertures formed in them for receiving a shaft 82, which also extends through brackets 84 and the levers 65. Similarly, the lower ends of the links 80 have apertures formed in them in alignment with apertures in the forward or right end of the levers 66 (Figs. 6 and 7) for receiving a shaft 83. The brackets 84 are pivotally mounted on the shaft 82 adjacent the outer end thereof and will thus move vertically when the right ends of the levers 65 and 66 move up or down. Both of the brackets 84 are provided with a series of apertures 85, as shown most clearly in Fig. 3, for receiving the upper end of a contractile spring 86, the lower end of which is attached to the bottom flange of the cross brace 81. In this manner, the brackets 84 are biased to rock in a counterclock-

wise direction, as viewed in Figs. 6 and 7, about the shaft 82, but the rocking of the brackets 84 is blocked by an abutment member 87 fixed to the links 80, whereby the bracket 84 is prevented from rocking beyond the position shown in full lines in Figs. 6 and 7 about the shaft 82 in a clockwise direction. The lower left hand corner of each of the brackets 84, as viewed in Figs. 6 and 7, is rounded so that the brackets may be rocked counterclockwise against the action of the springs 86, as will be described hereinafter.

Mounted upon the tube 62 adjacent one end thereof, is a clamp 88 made of non-magnetic material, which is clamped tightly onto the tube and carries a small permanent magnet 89 attached to it adjacent its lower end by means of a screw 90. The permanent magnet 89 will thus be rocked with the tube 62 and will move into operative association with a magnetically operated switch 91. When the clamp 88 rocks with shaft 62 to carry the magnet 89 to operative association with the magnetically operated switch 91, it will cause the closure of the pair of contacts 30 which compose a part of the magnetically operated switch 91. The contacts 30 are connected to a pair of leads 92, in turn connected to the extending ends of leads 93 leading into a conduit 94, as shown in Figs. 5, 6 and 7, to connect the contacts 30 to the start switch 29 and timer 28.

Mounted on the brackets 84, and normally held in a horizontal position thereby is a table or tray 101, which is adapted to substantially close the bottom of the chute 40, and onto which articles molded in the press will be directed. This table or tray 101 will move downwardly in an arcuate path from the position shown in Fig. 6 to the position shown in Fig. 7, upon the receipt thereon, of a part ejected from the press and will move downwardly until the right end of the table (Figs. 6 and 7) engages the left hand surface of camming member 102 mounted upon the upper end of the bell crank lever 51. Upon operation of the bell crank lever 51 by the linkage mechanism, including lever 41, collar 46, and rod assembly 45, the table 101 will be tilted counter-clockwise to the position shown by the dot and dash lines in Fig. 7, as will be described more in detail in connection with the following brief description of the mode of operation of the apparatus. Tilting of the table 101 by camming member 102 will eject a part therefrom and also tend to push the table back to its normal position since the springs 86 will exert pressure to return the plate to a horizontal position.

After a supply of moldable material has been placed in a hopper (not shown) for direction to the press through the nozzle 42 and the platens or die block 14 and die member 15 are heated to a predetermined temperature, the apparatus may be started in operation by closing the switch 29. The cycle of operation of the apparatus starts with the movable die member 15 in approximately the position shown where the piston 17 is almost at the upper end of its travel. Then, upon closure of the start switch 29, the timer 28 will feed current to energize coil 27 and fluid under pressure will be supplied to the lower end of the cylinder 18, thus to move the movable die member 15 to its uppermost position. As the movable die member 15 moves to its uppermost position, the material feeding means (not shown) will also be operated under control of the timer 28 and material will be fed through nozzle 42 into the die 43. The timer 28 is so arranged that immediately after the piston 17 reaches its uppermost position, cur-

rent will be directed from the timer 28 to the coil 26 to reverse the valve 21 and start the movable die member 15 moving downwardly. During the movement of the movable die member 15 from its closed position with member 14 to the position shown in Fig. 1, the rod assembly 45 will eject a processed part from the die 43 and the timer 28 will cause air to be directed under pressure through the nozzle 41 to eject the part or parts from the die 43 into the chute 40, the article or articles having been pushed up out of the cavity by the rod assembly 45.

The part ejected from the die 43 by the blast of air from the nozzle 41 will drop through chute 40 onto the table 101 and will move the table 101 to the position shown in Figs. 1 and 7. Continued downward movement of the movable die member 15 will cause the collar 46 to engage and actuate lever 47 and will thus serve to actuate the bell crank lever 51. Actuation of the bell crank lever 51 will cause the table 101 to be tilted to slide the part or parts off the table into a suitable container, such as shown at 110. When the table 101 moves from its upper position, as shown in Fig. 6, to its lower position, as shown in Fig. 7, it will rock the tube 62 and move the permanent magnet 89 to a position where it will close contacts 30 of switch 91. The timer is so arranged that closure of switch 29 will initiate a cycle of it and the circuit to the timer will then be automatically maintained at all times except during that interval when a part should be resting on the table 101. In the interval, when the table 101 should be in its lowermost position, the circuit for maintaining the timer 28 in operation may be closed by the switch 91 and if the contacts 30 of the switch 91 are closed due to the table 101 moving to its lowermost position, the timer circuit will be maintained and continued cycles of operation of the apparatus will be performed.

As soon as the cam member 102 tilts the table 101 to the position shown in dot and dash lines in Fig. 7, the molded part being ejected from the table, the table 101 will rise to the position shown in Fig. 6. As the timer 28 continues its cycle, the molding of the part will take place and after a predetermined time, as determined by the setting of the timer 28, the movable die member 15 will again move upwardly and will be stopped in a position shown in Fig. 1 unless the contacts 30 had been closed by the permanent magnet 90 being rocked under the influence of a part on the table 101. If the table 101 does not move to the position shown in Fig. 7, the bell crank lever 51 will be rocked by the lever 47, but it will pass beneath the table 101. After the table 101 has been tilted to discharge a part from it into the container 110,

it will move to its uppermost position, as shown in Fig. 6, ready to receive a part ejected from the molding die 43.

What is claimed is:

- 5 1. The combination with an article forming apparatus of a stationary framework, a pair of pantograph levers individually pivoted on said framework, a table supporting member pivotally connected to said levers to move in an arcuate path while held in a vertical position, a table pivoted on said member to receive articles formed in said apparatus, means normally tending to hold said table at right angles to said member during movement of said member, and means operated by the forming apparatus during its operation to form articles for tilting said table with respect to said member from its normal position when the table is in a position to be unloaded, said latter means including a reciprocatory link operable by said forming apparatus, a leverage mechanism, a cam member carried by said mechanism arranged in the path of and engaged by said table as it reaches its unloading position, and an actuator carried by said link for operating said mechanism during operation of said forming apparatus to form articles for tilting said table.
- 10 2. The combination with an article forming apparatus of a stationary framework, a pair of pantograph levers individually pivoted on said framework, a table supporting member pivotally connected to said levers to move in an arcuate path while held in a vertical position, a table pivoted on said member to receive articles formed in said apparatus, means normally tending to hold said table at right angles to said member during movement of said member, and means for tilting said table with respect to said member from its normal position when the table is in a position to be unloaded, said latter means including a reciprocatory link, a leverage mechanism, a cam member carried by said mechanism arranged in the path of and engaged by said table as it reaches its unloading position, and an actuator carried by said link for operating said mechanism.
- 15 30 3. The combination with an article forming apparatus of a stationary framework, a pair of pantograph levers individually pivoted on said framework, a table supporting member pivotally connected to said levers to move in an arcuate path while held in a vertical position, a table pivoted on said member to receive articles formed in said apparatus, means normally tending to hold said table at right angles to said member during movement of said member, and means for tilting said table with respect to said member from its normal position when the table is in a position to be unloaded, said latter means including a reciprocatory link, a leverage mechanism, a cam member carried by said mechanism arranged in the path of and engaged by said table as it reaches its unloading position, and an actuator carried by said link for operating said mechanism.
